Attorney.

UNITED STATES PATENT OFFICE.

EMMA H. ISHAM, OF CINCINNATI, OHIO.

WASHING-MACHINE.

SPECIFICATION forming part of Letters Patent No. 612,110, dated October 11, 1898.

Application filed November 18, 1897, Serial No. 658,992. (No model.)

To all whom it may concern:

Be it known that I, EMMA H. ISHAM, a citizen of the United States, and a resident of the city of Cincinnati, in the county of Hamilton 5 and State of Ohio, have invented certain new and useful Improvements in Washing-Machines, of which the following is a specification.

The several features of my invention and 10 the various advantages resulting from their use, conjointly or otherwise, will be apparent from the following description and claims.

In the accompanying drawings, making a part of this application, and in which similar 15 letters of reference indicate corresponding parts, Figure 1 is an exterior view in perspective of a washing-machine constructed in accordance with the principal features of my invention. Fig. 2 is a vertical central section 20 of the tank (cylinder) and bottom of this machine, the dasher and its accompaniments and its rod and handle, as well as the stopples in the barrel, being shown in elevation. Fig. 3 is a top view of the dasher and its accompaniments, the upper part of the central 25 rod and its handle being cut away to better enable the dasher to be seen. Fig. 4 is a view of the under side of the dasher and its accompaniments. Fig. 5 represents a vertical section of the dasher and its accompaniments, taken in the plane of the dotted line 30 55 of Fig. 3, the bars and guide-rods with their heads and their springs being left in elevation. Fig. 6 is an enlarged detail of a guide-rod, spring, cylinder, and of the adjacent 35 portion of a holding-bar, the cylinder being shown in vertical central section. Fig. 7 is an edge elevation of the dasher and adjacent portion of the dasher-rod and accompaniments, the latter illustrating an additional 40 feature of my invention. Fig. 8 represents a view taken partly in section and partly in elevation similarly to that of Fig. 5, the section being taken in the plane of the dotted 45 line 8 of Fig. 7.

A indicates the tank, of cylindrical form, having the side-encircling wall B and bottom C and top or cover D. The upper surface of the bottom C is provided with corrugations C², 50 and these preferably run across the bottom in parallel lines. These corrugations may be formed in the surface of the bottom itself;

but where the latter is of wood they are usually formed in a sheet C³ of metal, zinc or a zinc-coated metal being the kinds preferred, 55 and this corrugated sheet is duly fixed to the bottom. In plan view this sheet corresponds in shape to that of the bottom, which it covers.

E indicates a dasher having a dasher-rod F concentrically connected thereto and preferably in a rigid manner. This dasher-rod extends up through the center of the cover and is preferably provided with a cross-handle F² the better to enable the rod F and its dasher E to be reciprocated. The opening D² of the cover 60 through which the dasher-rod passes is sufficiently large to admit of the easy reciprocation of this rod through it. The cover D is suitably fixed to the cylinder B, so as to be incapable of lateral displacement while in 65 working position. One mode of thus fixing it consists in providing it with an extension D³, which fits closely within the cylinder B, and with a flange D⁴, extending down outside of the cylinder B and close thereto. 70 Either of these would alone be sufficient to prevent lateral displacement of the cover relative to the cylinder B. If either were to be dispensed with, the extension D³ would be retained; but the flange D⁴ performs an 75 important and additional function in the machine—to wit, it helps to make the connection between the cover and cylinder liquid-tight to the extent that water and soap-suds thrown or brought up by the dasher are 80 the better prevented from escaping past the cover and thence running down the outside of the tank. A further construction I employ in furtherance of this last-named end consists in making the upper edges of the 85 cylinder incline inward. This bevel B² operates to cause all the liquid which comes up to the cover, at the edge thereof, past the extension D³ to quickly run back into the tank. 95

The dasher is provided on its under side with corrugations E², and these corrugations are preferably formed as those of the bottom.

At the bottom of the dasher E are bars H, elastically held against the bottom of the 100 dasher and capable of being drawn out to place clothes above them—viz., between them and the dasher. The preferred means for thus combining the bars H with the dasher

are as follows: The bar is provided with guide-rods H^2 , which pass up into passages H^3 in the dasher. These openings have cylindrical walls H^4 , and these walls, if the dasher is not very thick, will extend up above the upper surface of the dasher, as shown. The better to allow the rods to each receive a spring H^5 , coiled around them, these rods are of a much smaller diameter than the diameter of the opening, and the only part allowed to remain large is an enlargement or disk H^6 at the upper end of each rod. This closely fits within the cylinder and the rod plays closely through the opening H^7 below. Thus the rod H^2 is always truly guided. The spring H^5 rests upon a stop, as the bottom of the cylinder H^8 , and its upper end is beneath the disk H^6 . Thus constructed, when the bar H is drawn down (away) from the dasher E (see Figs. 5, 6, and 8) the guide-rods H^2 are likewise drawn down and the springs H^5 are compressed. When the pull upon the bars H has ceased, the springs H^5 will retract the bars to their first position. (See Figs. 2 and 7.) Where it is not desired to manipulate the bars H by directly handling them, I provide a device for otherwise depressing them—to wit, a central rod H^9 is fixed to the bar H and passes up through the dasher E and extends above the latter. The upper end of this rod H^9 is provided with a button or thumb-push H^{10} . By pressing down on this push H^{10} the bar H is depressed, as shown in Fig. 8. The corrugations E^2 , with which the dasher is provided, may be formed in the bottom of the dasher itself; but the latter, for the sake of lightness, is preferably formed on a metal sheet, and this preferably forms part of a metal box J in which the dasher is inclosed. This metal box affords a convenient structure to which the cylinders H^4 can be attached. The box is connected to the dasher by means of screws. Such screws J^2 connect the metal top to the dasher. A ferrule J^3 from the box embraces the dash-rod and is suitably secured thereto, as by screws J^2 . The dasher has vertical openings E^3 through it, and these permit the liquid, except so far as prevented by the clothes, to pass through the dasher, and thus allow it to move up and down the more readily and the better to agitate and mix the suds.

The lid can be fastened down, as by a hook K engaging a staple K^2 , fixed in the outside of the cylinder B . For the ready admission of water or soapsuds after the cover D has been secured in place on the tank an opening D^5 is present and is provided with a stopple D^6 . The latter may be secured by a chain D^7 to the cover, as shown. The lining D^8 of the opening D^5 is preferably metal.

For the purpose of enabling the washing liquid to be readily removed after the operation of washing the articles to be cleansed has been concluded an opening B^3 in the lower end of the tank, and preferably lined with metal B^6 , is closed by a stopple B^4 . This

latter may be secured from being lost by means of a cord or chain B^5 .

The method in which I operate my invention is substantially as follows: The cover is removed and the dasher withdrawn. The articles to be washed are placed between the bars H and the dasher. This is done by depressing a bar H and passing the articles to be washed between the bar and the dasher and then releasing hold of the bar. The latter, through the agency of the springs H^5 , will draw the bar toward the dasher and elastically hold the articles to be washed against the dasher and secure them from displacement. The dasher, thus provided at its under side with the articles to be washed, is now replaced in the tank.

The tank is to be supplied with sufficient water and soap or bluing or whatever, if anything, is to be added to the water to be used in the operation of washing either before the dasher is replaced in the tank or after it has been reinserted in the tank. The cover having been put in place the operation of washing is begun, and consists in reciprocating the dasher at times, and for the most part in rotating the dasher, so that the articles to be washed will be rubbed between the dasher and the bottom of the tank. The operation of thus washing the articles at the dasher is very soon completed, whereupon the articles thus washed are removed. Should it now be desired to wash another lot of articles, the aforescribed operation is repeated. When the wash is completed, the liquid in the tank is drawn off through opening B^3 in the tank.

My invention is of great value in small apartments or flats and suites of rooms. It enables the lady of the house to do the washing, especially of the smaller articles of clothing or laces, &c., without soiling the apartment or her own clothing or hands.

What I claim as new and of my invention, and desire to secure by Letters Patent, is—

1. In a washing-machine, a dasher having reciprocatory bars, extending across the working face of the disk of the dasher, and springs fixedly attached thereto, substantially as and for the purposes specified.

2. In a washing-machine, a dasher having bars located at its bottom, and extending across the working face of the latter, and springs fixedly attached to the bars and adapted to retract the latter, substantially as and for the purposes specified.

3. In a washing-machine, a dasher having separable bottom bars, provided with rods having disks, and cylindrical walls in the dasher receiving the disks and rods and carrying a stop H^8 , and springs within the cylindrical walls compressed between the disks and a stop below, substantially as and for the purposes specified.

4. In a washing-machine, a dasher having separable bottom bars extending across the dasher, and devices for elastically pressing the bars to the bottom, and vertical rods sep-

arate from the springs for pushing the bars from the dasher, substantially as and for the purposes specified.

5. In a washing-machine, a dasher having separable bottom bars, and the rods having disks, and cylindrical walls in the dasher receiving the disks and rods and carrying a stop H^8 , and springs within the cylindrical walls compressed between the disk and the 10 stop below, and the reciprocating rod H^9 connected to the bar H , and having the push-piece as H^{10} , substantially as and for the purposes specified.

6. In a washing-machine, a dasher, consisting of a metallic inclosure corrugated at bottom, and embracing a wooden disk, and having at top a ferrule receiving the dasher-rod, in combination with cylinders H^4 held in the dasher, and bars H , and rods for advancing the bars and respectively working in said cylinders and springs for retracting the rods, substantially as and for the purposes specified. 15 20
